Primary Examiner — Philip S Hyder

(74) Attorney, Agent, or Firm — Oppedahl Patent Law Firm LLC

(57) **CLAIM**

The ornamental design for an ergonomic rotary cutter, as shown and described.

DESCRIPTION

FIG. 1 is a perspective view;

FIG. 2 is a front view;

FIG. 3 is a rear view;

FIG. 4 is a top view;

FIG. 5 is a bottom view;

FIG. 6 is a left side view; and,

FIG. 7 is a right side view.

The broken lines appearing on the surfaces of the ergonomic rotary cutter, form no part of the claimed design.

1 Claim, 7 Drawing Sheets(56)
